ELECTRICAL CIRCUITS

Clarence W. Hansell, Port Jefferson, N. Y., assignor to Radio Corporation of America, a corporation of Delaware

Application October 31, 1932, Serial No. 640,370

8 Claims. (Cl. 250—17)

This invention relates to apparatus for eliminating undesired amplitude variations in the output circuits of, for example, phase and frequency modulated transmitters.

5 In practice, the power amplifiers used in phase and frequency modulation transmitters, introduce ripples or undesired amplitude variations in the final output to be transmitted. These variations arise chiefly from the use of alternating currents to heat the filaments of the power amplifiers and from ripple in the negative bias voltage and plate potential when derived from rectifiers or a commutator type of generator.

The principal object of my present invention 15 is to provide a method and means for eliminating these undesired amplitude variations. Briefly, to do so, a portion of the amplifier output is rectified so as to obtain waves which are a copy of any undesired ripple or amplitude variation in the 20 amplifier output circuit. This wave copy is then applied to the amplifier in such a way as to modulate its output in reverse sense whereby the introduced modulation effectively balances out nearly all of the undesired amplitude changes.

25 My present invention is more fully described hereinafter with the aid of the accompanying drawings, wherein,

Figure 1 is a wiring diagram of a phase or frequency modulation transmitter having incorporated therein an arrangement according to my present invention for eliminating undesired amplitude variation due to fluctuations in power supply for the power amplifier;

Figure 2 is a modification of the arrangement 35 shown in Figure 1 wherein correcting modulation is applied to an early stage of a plurality of cascaded amplifiers; and,

Figure 3 is a further modification wherein correcting potentials are applied to the screen grids 40 of a power amplifier to eliminate from a phase or frequency modulated transmitter undesired amplitude variations.

Turning to Figure 1, a source of frequency or phase modulated waves 2 energizes through 45 transmission line 4 and tunable input circuit 6, pushpull connected electron discharge devices or vacuum tube amplifiers 8, 10. The amplifier tubes 8, 10 are cross-neutralized as shown, to prevent parasitic oscillation generation and are provided with a tunable output circuit 12 in turn energizing a radiating antenna 14.

Anode potential for tubes 8, 10 is supplied from rectifier unit 16 energized with commercial 60 cycle current from transformer 18. The rectifier 55 unit 16 also supplies through lead 20 and resistor

22 negative grid biasing potential for vacuum tubes 8, 10. The filaments or cathodes of the tubes 8, 10 are energized to an electron emitting condition with alternating currents through the action of transformers 24, 26.

5 Due to fluctuations in the plate potential supplied through lead 28, as well as fluctuations in grid bias supplied through conductor 20, as well as variations in filament voltage and current because of their energization to an electron emitting condition with alternating currents, it will be found that the high frequency phase or frequency modulated energy in the output circuit 12 will also have an undesired ripple or amplitude variation. To eliminate this undesired amplitude variation to the output circuit 12 there is coupled a diode rectifier 30 by means of an induction coil 32. The rectifier is by-passed for high frequency currents by means of bypassing condenser 34. The output of the rectifier will be a copy of the undesired amplitude variation or ripple appearing in the output circuit 12, and this wave copy is applied through variable tap 32 to resistor 22 in such a way as to vary the grid bias or, in other words, modulate 25 the power amplifiers 8, 10 in such a direction as to balance out the undesired ripple in the output circuit 12.

In the arrangement shown in Figure 2, the 30 rectifier 2 supplies the cascaded amplifier stages with anode potential through conductors 28. The cascaded amplifiers 40, 42, 44 are preferably of the pushpull type although they need not be limited thereto. The filament heating current sources for the cathodes of the stages 42, 35 44 have not been shown, but may be either alternating current circuits, or direct current circuits, and also, the grid biasing potentials need not be derived from an A. C. source, but, the grid polarizing arrangement may be of the self-40 biasing type such as a grid leak resistor 46 of the pushpull cross-neutralized stage 44, or, the grid biasing potential may be derived from a constant source of potential such as battery 48 applying negative bias through resistor 50 to the 45 grids of the tubes forming amplifier 40.

To eliminate undesired amplitude variation in the final output circuit 52 of amplifier 44, a portion of the output is rectified by rectifier 30 and fed through conductors 54, 56 to the grid biasing 50 circuit 48, 50 for the grids of the tubes forming amplifier 40. By adjusting the direction and magnitude of applied rectified waves from rectifier 30 to the grids of tubes 40, the energy in the output circuit 52 will be modulated in a reverse 55

sense so as to substantially balance out the undesired ripple or amplitude variations normally present. Consequently, energy radiated over antenna 14 will be of substantially constant amplitude and modulated in frequency or in phase dependent upon the character of modulation source 2.

If desired, I may, of course, connect rectifier 30 of both Figures 1 and 2 in series with the negative biasing source to the grids of the amplifier tubes. In this case it is preferable to connect a resistance of suitable value across the D. C. output of rectifier 30 to permit the passage of rectified grid current in opposition to the rectifier.

It is not necessary that the correcting potentials be applied to the usual control electrodes or grids of an electron discharge device amplifier. As shown in Figure 3, rectifier 30 coupled to the output circuit 12 of pushpull connected screen grid electron discharge devices 60, 62 feeds through conductors 64, 66 a replica of the amplitude variations appearing in circuit 12 to the screen grid voltage dropping resistor 68. Consequently, the screen grids 70, 72 grounded by means of radio frequency by-passing condenser 74 will be subjected to potentials which will balance out or cause the cancellation of undesired amplitude ripple appearing in the output circuit 12. In this case also I may connect rectifier 30 in series with the resistor 68, as an alternative arrangement.

Having thus described my invention, what I claim is:

35. 1. In electrical apparatus for reducing power supply noise, an amplifier comprising an electron discharge device having an anode a cathode and a control electrode, an input circuit coupled to said control electrode, an output circuit connected to said anode, a source of modulated electrical waves coupled to said input circuit, a rectifier coupled to the output circuit of said amplifier for deriving the amplitude component from said modulated waves, and, a circuit 40 coupled to the input circuit of said amplifier and to the output of said rectifier for impressing on the energy in said amplifier compensating energy from said rectifier whereby the output of said amplifier is a modulated wave substantially 45 free of all amplitude variations.

50. 2. In combination, a source of modulated electrical waves, an amplifier amplifying energies from said source, said amplifier producing amplitude variations in the amplified output thereof, a rectifier coupled to the output circuit of said amplifier for deriving therefrom a copy of all of the amplitude variations in said modulated waves, and, a circuit for applying the wave copy to said amplifier in such a way as to 55 eradicate substantially all amplitude variations in the output circuit of said amplifier.

60. 3. In combination, a source of modulated waves, an electron discharge device amplifier coupled to said source for amplifying waves from said source, said amplifier comprising an electron discharge device having an anode a cathode and a control electrode, an output circuit for said amplifier, a rectifier coupled to the output circuit of said amplifier for deriving therefrom waves corresponding to all amplitude variations in the output circuit of said ampli- 65

70. fier, and, a circuit for applying the output wave energy of said rectifier to the control electrode of said amplifier whereby all amplitude variations in the output circuit of said amplifier are substantially eliminated.

4. In combination, a source of phase or frequency modulated waves, an amplifier for amplifying the phase or frequency modulated waves, said amplifier producing undesired amplitude variations in the amplified waves, a rectifier rectifying a portion of the amplified waves to obtain a copy of all amplitude variations in the amplified waves, and, a circuit for applying the wave copy to the amplifier in such a way as to balance or neutralize substantially all of the amplitude variations introduced by the amplifier.

5. In electrical apparatus for reducing power supply noise, an amplifier comprising an electron discharge device having an anode, a cathode, a screen-like electrode and a control electrode, an input circuit coupled to said control electrode, an output circuit connected to said anode, a source of modulated electrical waves coupled to said input circuit, a rectifier inductively coupled to the output circuit of said amplifier for deriving the amplitude component from said modulated waves, and, a circuit coupled to the screen-like electrode in said amplifier and to said rectifier for combining with the wave energy in said amplifier compensating energy from said rectifier whereby the output of said amplifier is a modulated wave substantially free of all amplitude variations.

6. In combination, a source of modulated electrical waves, an amplifier amplifying energies from said source, said amplifier producing amplitude variations in the amplified output thereof, a rectifier inductively coupled to the output circuit of said amplifier for deriving therefrom a copy of all of the amplitude variations in said modulated waves, and, a circuit for applying the wave copy to said amplifier in such a way as to eradicate substantially all amplitude variations in the output circuit of said amplifier.

7. In combination, a source of modulated waves, an electron discharge device amplifier coupled to said source for amplifying waves from said source, said amplifier comprising an electron discharge device having an anode a cathode and a control electrode, an output circuit for said amplifier, a rectifier inductively coupled to the output circuit of said amplifier for deriving therefrom waves corresponding to all amplitude variations in the output circuit of said amplifier, and, a circuit for applying the output wave energy of said rectifier to the control electrode of said amplifier whereby all amplitude variations in the output circuit of said amplifier are substantially eliminated.

8. In combination, a source of phase or frequency modulated waves, an amplifier for amplifying the phase or frequency modulated waves, said amplifier producing undesired amplitude variations in the amplified waves, a rectifier, inductively coupled to said amplifier, rectifying a portion of the amplified waves to obtain a copy of all amplitude variations in the amplified waves, and, a circuit for applying the wave copy to the amplifier in such a way as to balance or neutralize substantially all of the amplitude variations introduced by the amplifier.

CLARENCE W. HANSELL.
